(57) **CLAIM**

The ornamental design for a electrified wire fence coupler, as shown and described.

DESCRIPTION

FIG. 1 is a front isometric view of a electrified wire fence coupler showing my new design;

FIG. 2 is a right elevated view of the electrified wire fence coupler, the opposite side being a mirror of the image shown;

FIG. 3 is a rear elevated view of the electrified wire fence coupler;

FIG. 4 is a top plan view of the electrified wire fence coupler, the bottom side being a mirror of the image shown; and,

FIG. 5 is a rear perspective plan view of the electrified wire fence coupler. The portions shown in broken lines are included for the purpose of showing environment and form no part of the claimed design.
